UNITED STATES PATENT OFFICE.

OCTAIVE DEGRENIER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

CUTTER.

Application filed May 10, 1920. Serial No. 389,190.

To all whom it may concern:

Be it known that I, OCTAIVE DEGRENIER, a citizen of the United States, residing at Southbridge, in the county of Worcester and 5 State of Massachusetts, have invented certain new and useful Improvements in Cutters, of which the following is a specification.

This invention relates to improvements in glass cutting machines and has particular 10 reference to a machine intended for use in the cutting of ophthalmic lenses or similar articles.

One of the leading objects of the present 15 invention is the provision of a novel and improved form of cutter which may be power actuated for the cutting operation, thus greatly increasing the possible speed of production of cut lenses or blanks, as well as greatly reducing the work of the operator 20 in satisfactorily cutting the articles.

A further object of the present invention 25 is the provision of a novel and improved form of glass cutter which shall insure a constant pressure between the cutting point and the article to be cut during the operation, and which shall be automatic in operation, obviating the variations in pressure and cutting effect present when the pressure 30 is under control of various individual operators.

Other objects include a simplification of 35 construction and operation of a cutter and improvement in the arrangement of parts for accessibility and holding and operating upon the work, and in the general details of 40 construction, as should be readily apparent by reference to the following specification taken in connection with the accompanying drawings, and it will be understood that I 45 may make any modifications in the specific details of construction shown and described within the scope of the appended claims without departing from or exceeding the spirit of the invention.

Figure I represents a front view of a cutter embodying my improvements.

Figure II represents a side elevation thereof.

Figure III represents a fragmentary sectional view through the automatic clutch.

Figure IV represents a similar view showing the clutch in disengaged relation.

Figure V represents a horizontal sectional view as on the line V—V of Figure II.

55 In the drawings, the numeral 1 designates

a table or support for my improved cutter, having secured thereon the cutter base 2 provided with the upright bracket portion 3 terminating in the bearing 4 for the spindle 5. Said base is further provided with a vertically shiftable table member 6 adapted to be pressed upwardly as by the lever 7 pivoted at 8 to the base and bearing at the one end against the stud 9 on the table and having on the other end the depending rod 10 which projects downwardly through the table 1. This rod has mounted thereon beneath the table 1 the tension spring 11, preferably enclosed within the sleeve 12 bearing at one end against the table 1 and at the other 70 against the adjusting nut 13, which may be tightened to bring any desired tension against the rod 10 and thus through the lever 7 to force the table 6 upward with desired pressure. This pressure may be counteracted when desired by the pressure release lever 14 pivoted to the base and having one end extending beneath the outer portion of the lever 7 and the opposite end connected by the link 15 with a control pedal 16 so that depression of the pedal will rock the lever 14 raising the outer end of the lever 7 against the tension of the spring 11 and allow the table to move downwardly and rest against the base 2. Releasing of the tension of the 75 pedal on the other hand will allow the spring 11 to exert its tension to force the table upward. It will thus be seen that while the pedal controls the spring tension the actual amount of pressure is dependent 80 on the adjustment of the spring and is always the same irrespective of change of operators or the like, thus differing from the systems employed in the past in which the pressure was applied by hand to the outer 85 end of a shift lever, such as the lever 7, the pressure then varying with different operators or with the way the particular operator happened to feel, being liable to be irregular as well as very tiring when a large amount 90 of cutting had to be done.

It will be understood that the glass blank, or the like, 17 in use rests on the table 6, while to operate upon the blank I make use of the cutter 18 carried by the swinging arm 19 whose position is controlled by the engagement of its adjustable contact shoe 20 with the former or pattern 21 secured on the bushing 22 mounted in the bracket bearing 4. The swinging cutter arm 19 is 105 110

carried by an arm 23 rigidly secured to the lower end of the shaft 5 and having a steady portion 24 above the swinging cutter arm which rides on the guide 25 also 5 carried by the bushing. The former is preferably of split or two part type to make it readily interchangeable, being slipped around as in a groove at 26 on the bushing or sleeve member 22 and secured in position 10 as by the spring clasps 27. To cause rotation of the spindle and thus the carrying around of the cutter 18 I preferably mount above the bearing 4 on the shaft or spindle 5 the clutch disc 28 having therein a sliding pin 29 normally pressed downward by the blade spring 30 which lies in the clutch pin track 31 in the upper face of the clutch disc 28. This clutch pin 32 rides in a recess in the drive pulley 33, this recess 34 also 15 holding the clutch pin spring 35 which is of just sufficient strength to cause the pin to readily drop downward and engage against the shoulder 36 above the pin 29.

The operation of this clutch mechanism, 25 which is of extremely simple character and may be varied if desired, should be readily understood by a comparison of Figures III and IV, from which it will be seen that when the pin 29 rides up on the control stop 30 37 it raises the blade spring 30 on a level with the remainder of the clutch pin track 31 so that the pin 32 will slide freely around in the track 31, but if the member 37 be disengaged from the pin 29, the pin and its 35 blade spring will drop so that as the clutch pin comes along in the track 31 it will slide down on the blade spring and engage with the shoulder 36. When the pin 39 is again raised it will force the clutch pin upward 40 and disengage the parts. Power is continuously applied during the operation of the machine to the drive pulley 33 as by the medium of the belt 38 rotating the latter continuously at a slow rate of speed, while 45 intermittently driving the cutter as the clutch control 37 is moved into or out of engagement with the pin 29.

To control the member 37 I may suitably 50 mount it, for example, in the bearings or bracket portions 39 on the frame 3 with a vertical rocking portion 40, a spring 41 normally springing the same inward into position to engage with the pin 29 and its head having a cam or inclined portion 42 up which the control pin 29 may ride as the disc is turned in that direction, thus causing automatic disengagement of the clutch. The lower end of the rock member 40 projects laterally for engagement with the end 55 of the clutch control rod 43, having the thumb piece 44 for pressing the rod inward to rock the member 40 and momentarily disengage the control 37 from the pin 39 until the pin moves by the control, when it is 60 allowed to swing back automatically and

disengage the cutter. If preferred, in place of or supplementing the control 43, there may be a suitable operating connection 45 between the lever 14 and the rock shaft 40, to the end that when the lever is released to 70 allow the pressure spring to come in operation the spring 46 will continue to draw up the lever 14, rocking the shaft after the lens table has been raised by its spring pressure to temporarily disengage the members 29 and 37, the machine then being entirely automatic in operation, in that the operator merely places the glass in position and releases the pressure on the pedal, when the glass is first automatically raised, 80 pressed against the cutter, and the cutter actuated to make a complete revolution, forming the desired cut on the glass, after which the cutter automatically stops and it is then necessary for the operator to depress the pedal temporarily releasing the retaining pressure and shift the stock being cut lengthwise in the case of a large piece of stock, or insert a new piece again releasing the pedal when the cutting operation will 85 be performed.

To retain the work in proper position on the table I preferably make use of a suitable clamp 46 to steady the work in position on the table, although it will be understood that this may be dispensed with and the work held at the edges if desired, in view of the fact that the work itself does not rotate but remains stationary during the cutting operation. It will also be noted that while I have particularly described a power lens cutter, the principles here employed are 90 equally applicable in many other instances and to advantage. In this connection particular mention might be made of the automatic tension for insuring proper pressure and preventing undue pressure between the lens and cutting point, and also the automatic mechanism for disconnecting the cutter and the actuating wheel therefor when the cutter reaches a given point, making it 95 possible to actuate the driving wheel or disc 33 by hand in place of by belt power and yet the result of automatically disconnecting the cutter from its driving mechanism is retained when a complete cut has been made, preventing the cutter from a second time traversing the same ground, and thus eliminating the damage to either cutter or blank 100 in this manner.

I claim:

1. A lens cutter including a frame, a cutter carried by the frame and means for automatically forcing the article to be cut with uniform pressure in the direction of the cutter.

2. A lens cutter including a frame, a cutter carried by the frame, means for automatically forcing the article to be cut with uniform pressure in the direction of the cut-

- ter, and means for relieving the pressure in the direction of the cutter as desired.
3. A lens cutter including a frame, a cutter carried by the frame, means for automatically forcing the article to be cut with uniform pressure in the direction of the cutter, means for relieving the pressure in the direction of the cutter as desired, and means for adjusting the amount of said pressure.
- 10 4. A lens cutter including a work support, a cutter and power means for shifting the cutter over the work support.
5. A lens cutter including a base, a vertically shiftable table carried by the base, means for automatically shifting the table into operative position with a predetermined pressure, a cutter mounted above the table, and power driven means for revolving the cutter.
- 20 6. A lens cutter including a base, a vertically shiftable table carried by the base, means for automatically shifting the table into operative position with a predetermined pressure, a cutter mounted above the table, power driven means for revolving the cutter, and clutch mechanism for limiting the operation of the cutter automatically to a single complete revolution.
7. In a lens cutter, the combination with a base and a movable lens supporting table carried thereby, of a rock lever for lifting the table into operative position, a spring for resiliently actuating the lever, and a control device for counteracting the action of the spring.
- 30 8. A lens cutter including a base, a work support, a cutter for operation in conjunction therewith, and means for holding the work support and cutter in opposition at a predetermined constant pressure during the cutting operation.
- 40 9. A power lens cutter including a work support and a cutter, power driven mechanism for relatively shifting said parts to perform the cutting operation, and means for automatically stopping the cutting operation at a predetermined point.
10. In a lens cutter, the combination with a base and a movable lens supporting table carried thereby, of a rock lever for lifting the table into operative position, a spring for resiliently actuating the lever, a control device for counteracting the action of the
- spring, and means for adjusting the tension of the spring to control the pressure applied to the table.
11. A lens cutter including a work support, a bracket adjacent thereto, a rotatable cutter bearing spindle carried by the bracket, a rotatable actuating wheel for the spindle, and means for automatically disconnecting the spindle and actuating wheel at a predetermined point in the movement of the cutter.
- 15 12. A cutter of the character described including a base, a shiftable table carried by the base, means for resiliently actuating the table, and pedal controlled means for shifting the table into inoperative position.
- 25 13. A power lens cutter including a base, a shiftable non-rotatable table carried by the base, a power driven cutter mounted above the base for cooperation with the table, means for actuating the table in the direction of the cutter, and a control device 70 operable in one direction to actuate the cutter and in the opposite direction to move the table into inoperative position.
- 30 14. A device of the character described including a base, a lens supporting table carried by the base, a power cutter actuatable over the base, a trip controlling the movement of the cutter, and independent means for manually and for automatically actuating the trip.
- 35 15. A device of the character described including a base, a vertically slidable table carried by the base, a rock lever bearing at one end against the table for raising the same, pressure mechanism engaging the opposite end of the lever for shifting the lever and thus the table into operative position, a second rock lever carried by the base and having one end in position to engage the first mentioned rock lever and move it 80 against the action of its pressure mechanism, and a cam device carried by the opposite end of the lever, substantially as and for the purpose described.
- 40 90 In testimony whereof I have affixed my 100 signature, in presence of two witnesses.

OCTAVE DEGRENIER.
